COMBINED CAN OPENER AND
POURING SPOUT

William F. Punte, Syracuse, N. Y., assignor to
Continental Can Company, Inc., New York,
N. Y., a corporation of New York

Application January 21, 1935, Serial No. 2,783

4 Claims. (Cl. 221—23)

The invention relates to new and useful improvements in a combined can opener and pouring spout which is designed particularly for the opening of hermetically sealed cans and the dispensing of the liquid content therefrom.

5 An object of the invention is to provide a can opener and pouring spout which are formed as a unit structure and wherein during the opening of the can the spout is attached to the can and a sealed connection between the spout 10 and the can formed along the portion of the can adjacent the opening through which the contents are to be dispensed.

In the drawing:

15 Fig. 1 is a plan view showing a combined can opener and pouring spout embodying the improvements as applied to a container.

Fig. 2 is a longitudinal sectional view through the same.

20 Fig. 3 is an end view of the combined opener and pouring spout showing the cutting device, the sealing gasket and the spout, the parts being viewed from the inside of the spout. The can is also shown in broken lines.

25 The invention is directed to a combined pouring spout and cutter formed as a unit which is a very simple form of construction containing few parts so that it is cheap to manufacture. Attached to the spout is a projecting flange having a seat for a gasket which contacts with the 30 side wall of the can for making a sealed contact between the spout and the can. Also attached to the spout is a projecting handle which extends over the top of the can. Mounted on this handle is a retaining lug having a recess 35 on its inner face and this retaining lug is adapted to engage the end seam of the can at a point diametrically opposite the point where the spout is attached. The lug is so disposed that the gasket is held pressed against the can, making 40 a tight seal therewith when the lug is brought into contact with the end seam. Attached to this handle extending from the spout is a cutter which cuts the opening in the can as the 45 spout is applied thereto.

45 Referring more in detail to the drawing, the body portion of a can which is to be opened, is indicated at 1. The end 2 of the can is secured to the body portion by a double seam 3. This is the usual type of an hermetically sealed can 50 which may be used for packaging liquids, such as lubricating oils or the like. The spout is indicated at 4. It consists of a body portion 5 from which projects a pouring nozzle 6; said body portion has a depending flange 7, the inner

5 face of which is provided with a recess 8. In this recess is located a gasket 9. The flange 7 is arcuate in shape and conforms to the shaping of the outer wall of the can. The gasket 9 is similarly shaped and is adapted to make contact with the curved surface of the wall of the can body below the double seam and portions of the double seam.

55 Rigidly attached to the body portion 5 of the pouring spout is a handle 10. The handle 10 is of sufficient length so that it extends across the upper end of the can which is to be opened and projects beyond the same to a slight extent. This member 10 not only serves as a handle, but it also serves as a means for attaching and 15 positioning the spout relative to the can. It also serves as a carrying means for the cutter for forming an opening in the end 2 of the can. Said handle is provided with an opening 11. The cutter for severing the can end is attached to 20 the underside of the handle 10. Said cutter includes spaced side walls or wing members 12 and 13, which are connected by a main portion 14 constituting the primary cutting blade; said main portion 14 has a piercing point 14a and 25 cutting edges leading therefrom to the wing members. The side or wing members 12 and 13 are each formed with a projecting flange 15 which is adapted to rest against the underface of the handle 10 and a screw 16 associated with each 30 flange firmly secures the cutter to the underface of the handle 10. As shown in Fig. 2, the side members 12 and 13 are cut away at the upper end of the main portion forming the cutting blade 14 as indicated at 17. The opening 11 35 in the handle extends from one side member to the other.

Attached to the handle are two centering pins 18 and 19 and also a depending retaining lug 20. Said retaining lug 20 is provided with a recess 21 40 on its inner face and a tapered portion 22 at the inner side of the lug. When the can opener and spout is to be applied to a can, the piercing point is placed in contact with the end close to the double seam and as it is forced down into the can 45 by hand pressure on the upper side of the spout, the gasket will pass down alongside of the double seam and the outer face of the can. This downward pressure on the cutter will penetrate the can end and cut the end along diverging lines 50 substantially parallel with the end seam and thence along lines which are parallel and extending inwardly toward the center of the can. This will cause the portion 2a cut out of the end to roll downwardly and backwardly so as to give a 55

wide opening through which the contents of the can may be dispensed.

After the cutter is forced into the can to form the opening and the gasket placed adjacent the end seam, then the end of the handle or casting 10 is brought down so that the retaining pin 20 will pass over the end seam. The centering pins 18 and 19 will pass inside of the end seam and finally contact with the can end 2. The pins 10 contacting with the can end will limit the downward movement of the handle and insure the proper positioning of the spout on the can with the gasket against the can. When the tapered portion 22 of the lug contacts with the can end, 15 it will force the handle 10 to the right and this will draw the gasket 9 into tight sealing contact with the can wall and the can end seam. When the seam slips into the recess, the tool will be firmly attached to the can so that it is not easily 20 dislodged and at the same time the gasket will be held compressed so as to make a tight seal and to insure that the oil passing out through the opening 11 into the spout 4, will be dispensed through the nozzle 6. This sealing gasket is 25 preferably made of duprene or some other substance which is not attacked by the oil. In order to provide a proper vent opening for the can, the handle or casting 10 is provided with a piercing member 23 which is secured in any suitable way 30 to the handle and is shaped and dimensioned so as to penetrate the end, as indicated in Fig. 2 and thus provide a vent hole to admit air into the container as the contents are being poured from the spout.

It will be apparent from the above, that a very simple device has been provided for the opening of the can and the dispensing of the liquid contents thereof. Said device may be quickly attached to the can and when applied, the oil may 40 be dispensed through the spout rapidly and the can completely drained as the opening is formed very close to the end seam so that the oil is not trapped. It will also be noted that the gasket contacts with the end seam which is rigid and therefore a very tight seal may be produced with the pressure that is available when the retaining lug is passed beneath the end seam at the opposite side of the can. It will also be noted that the body portion of the spout and the gasket 45 extend throughout an arc of substantially 90° and this will give a funnel-shaped body portion to the spout to receive the oil and direct the same to the pouring nozzle.

It is obvious that minor changes in the details of construction and the arrangement of the parts, may be made without departing from the spirit of the invention as set forth in the appended claims.

Having thus described the invention, what I 60 claim as new and desire to secure by Letters Patent is:

1. A combined can opener and pouring spout comprising a body portion having a dispensing nozzle, a handle rigidly attached to said body portion, said body portion having a depending flange, a gasket attached to said flange and adapted to contact with the end seam and the wall of the can adjacent thereto, a cutter attached to said handle having a penetrating point and cutting edges for cutting the end wall of the can and rolling the metal thereof downwardly and inwardly to form a pouring opening, said handle

being extended across the can when applied thereto and retaining means rigid with said handle for engaging the end seam at a point diametrically opposite the gasket, said retaining means being disposed so as to hold said gasket in sealing contact with the end seam and body wall of the can. 5

2. A combined can opener and pouring spout comprising a body portion having a dispensing nozzle, a handle attached to said body portion, said body portion having a depending flange, a 10 gasket attached to said flange and adapted to contact with the end seam and the wall of the can adjacent thereto, a cutter attached to said handle having a penetrating point and cutting edges for cutting the end wall of the can and 15 rolling the metal thereof downwardly and inwardly to form a pouring opening, said handle being extended across the can when applied thereto and having positioning pins adapted to engage the can end inside the double seam and a 20 retaining lug adapted to engage the end seam at the outer side thereof, said retaining lug and positioning pins being disposed so that when in engagement with the can the gasket will be pressed against the end seam and body wall and 25 a tight seal formed therebetween.

3. A combined can opener and pouring spout comprising a body portion having a dispensing nozzle, a handle attached to said body portion, said body portion having a depending flange, a 30 gasket attached to said flange and adapted to contact with the end seam and the wall of the can adjacent thereto, a cutter attached to said handle having a penetrating point and cutting edges for cutting the end wall of the can and 35 rolling the metal thereof downwardly and inwardly to form a pouring opening, said handle being extended across the can when applied thereto and having positioning pins for engaging the can end inside of the end seam and a retaining 40 lug having a tapered portion and a recess above the tapered portion, said lug being disposed so that when pressed against the end seam, it will draw the gasket into tight sealing contact with the end seam at the opposite side of the can and 45 the body wall of the can.

4. A combined can opener and pouring spout comprising a body portion having a dispensing nozzle centrally thereof, said body portion being funnel-shaped for receiving and discharging the 50 liquid contents through said nozzle and having a depending flange, a gasket attached to said flange and adapted to contact with the end seam in the wall of the can adjacent thereto, substantially throughout the extent of the funnel, a handle 55 rigidly attached to said body portion and adapted to extend diametrically across the can end when applied thereto, said handle having an opening within the body portion of the spout, a cutter attached to the underside of said handle and having a cutting point adapted to penetrate and cut the end of the can so as to roll back the middle to form a wide opening, said cutter being disposed relative to the opening so that the contents will be dispensed through the opening in the handle 65 into the pouring spout, and retaining means rigidly carried by said handle and engaging the end seam of the can at a point diametrically opposite the gasket, said retaining means being disposed so as to hold the gasket pressed against the end 70 seam and body wall of the can.

WILLIAM F. PUNTE.
